UNITED STATES PATENT OFFICE

HERBERT G. IRWIN, OF AMARILLO, TEXAS

ACETYLENE GENERATOR

Application filed August 22, 1927. Serial No. 214,468.

This invention relates to improvements in acetylene generators of the carbide to water type in which an automatically controlled valve regulates the gravitation of granular carbide from a carbide container into a water container, the rate of carbide feed being determined by the rate of consumption of acetylene generated. The automatic feed control being the opposed gas pressure type 10 wherein a flexible diaphragm is arranged between two independent gas pressures whereby variation in one of the pressures will cause a movement of the diaphragm, the latter being connected so that its movement will 15 effect the operation of a carbide feed valve.

The object of my invention is to provide new and useful improvements in the automatic opposed gas pressure valve feed type of acetylene generator.

20 A further object of my invention is to simplify the contour and improve the appearance of the automatic opposed gas pressure valve feed type of acetylene generator.

A further object of my invention is to 25 move from sight the pressure tank of the automatic feed control.

A further object of my invention is to improve on the method of mounting the pressure tank of the automatic feed control.

30 A further object of my invention is to mount the feed control near the point of carbide feed.

With these and other objects in view, my invention consists in the arrangement, combination and construction of the various parts 35 of my improved device, as described in the specifications, claimed in the claims, and shown in the accompanying drawings, in which:

40 Figure 1 is a sectional view through a carbide hopper showing an automatic feed constructed and mounted in accordance with my invention, the automatic feed being also in longitudinal section.

45 Figure 2 is an elevation of the automatic feed removed from the carbide hopper shown in Fig. 1.

Figure 3 is a sectional view through a carbide hopper of an acetylene generator showing 50 an alternate form of my invention and

method of mounting the same, the automatic feed being also in section.

Figure 4 is an elevation of the automatic feed removed from the carbide hopper shown in Fig. 3.

Figure 5 is a view of the concave side of the feed control diaphragm spring.

Referring to the accompanying drawings, the upper portion of the water chamber of an acetylene generator is indicated by numeral 1, the carbide hopper 2, the hopper bottom 3 and the hand feed 4.

In Fig. 1 the automatic feed is mounted inside the carbide hopper pendent from the center of the hopper head 2A, and it consists 65 of a vertical pressure tank 5, a diaphragm housing of two separable sections 6 and 7, a feed control diaphragm 8, a diaphragm spring 9 and a carbide feed valve 10. The upper portion of the pressure tank terminates 70 in an annular shoulder 11, and a constricted threaded extension 12, that projects through the hopper head at the center thereof.

A nut 13 screws on the outer end of the tank extension clamping the tank to the under side 75 of the hopper head. Gas from the carbide hopper enters the pressure tank through the angular passageway 14, and the outlet of the pressure tank is through this passageway.

The needle valve 15, fitted in the tank extension 12 serves to close the passageway to confine gas in the pressure tank. The lower portion of the pressure tank terminates in the upper cupped section 6 of the control 80 housing. The control diaphragm is com-

posed of soft cured rubber having qualities of toughness and durability, saucer shaped and provided with a brim adapted to be clamped between the corresponding brims 85 of the housing sections. The diaphragm

spring is saucer shaped and disposed between the diaphragm and the lower flat section 7 of the diaphragm housing with its convex side toward the diaphragm. This spring normally 90 presses the diaphragm up into the hollow of the upper section of the diaphragm housing.

The spring may be cut from thin sheet stock of nonrusting spring metal, with equally spaced radial slits in its outer portion to form narrow spring sectors 9J. The 95

spring is saucer shaped and disposed between the diaphragm and the lower flat section 7 of the diaphragm housing with its convex side toward the diaphragm. This spring normally

presses the diaphragm up into the hollow of the upper section of the diaphragm housing.

The spring may be cut from thin sheet stock of nonrusting spring metal, with equally spaced radial slits in its outer portion to form narrow spring sectors 9J. The 100

spring sectors are all curved in one direction giving the spring a saucer like shape. The diaphragm and spring are clamped together by a concentric bolt with the nut on the under side of the spring. This bolt nut has a depending eye that clasps loosely with a corresponding eye on the upper end of the feed valve stem 10B, to form a kind of universal joint 16. The universal joint permits lateral movement of the carbide feed valve when the latter is lowered out of the feed opening and when pushed down and to the side by the hand feed. The cylindrical shield 7C, depending from the under side of the housing section 7 holds carbide away from the upper portion of the valve stem and prevents excess carbide over the feed valve. The hand feed consists of a smooth round poke rod 4, mounted for longitudinal alternate movement in a removable tubular guide 4D, disposed inclined through the side wall of the carbide hopper. The lower end of the poke rod is directed toward the side of the feed valve and upon pushing inwardly on the handle 4F, on the outer end of the rod, the inner end of the rod may be lowered to abut the side of the feed valve and push the valve open whereby to feed carbide from the hopper into the water chamber in raising the initial operating pressure in the generator. As for an instance, when the generator is refilled with carbide and water and all the fill openings closed the hand feed may be used to feed some of the carbide out of the hopper into the water chamber to generate acetylene enough to raise the desired working pressure in the generator. The needle valve 15 being in open position while the pressure is being raised may be closed when the desired pressure is reached. Upon drawing gas from the generator as in use, the pressure in the generator will be lessened and the pressure of gas confined in the pressure tank will press on the convex side of the feed control diaphragm by way of apertures 6H, in the upper diaphragm housing section 6. Thus the diaphragm will be flexed downwardly lowering the feed valve to feed more carbide into the water chamber which results in the generation of more acetylene. And presently sufficient acetylene will be generated to start the pressure in the generator upward and as pressure in the generator nears that in the pressure tank the diaphragm spring 9 moves the diaphragm upward closing the feed valve. The automatic feed performs repeatedly in much the same manner as consumption of gas is continued. By opening the needle valve 15 the automatic feed is put out of operation. With the needle valve open, gas in the pressure tank may equalize with that in the generator instead of pressing the diaphragm down as the pressure in the generator is lessened.

65 In Fig. 3 the automatic feed is mounted in

side the carbide hopper also and it consists of a horizontal pressure tank 5 disposed diametrically of the carbide hopper, a removable diaphragm housing of two separable sections 6 and 7, a feed control diaphragm 8, a diaphragm spring 9 and a carbide feed valve 10. One end of the pressure tank has a constricted threaded extension identical in configuration with the pressure tank in Fig. 1. The extension of this tank projects through the side wall of the hopper instead of projecting through the head of the hopper as in Fig. 1. The nut 13 screws on the outer end of the tank extension clamping the end of the tank to the inner periphery of the side wall of the hopper. The needle valve 15 in the projecting end of the tank is also the same as that in Fig. 1. The opposite end of the pressure tank is supported by the opposite side wall of the carbide hopper by means consisting in this instance of a band clamp 18, of two separable sections and a bracket 19. The feed control diaphragm housing depends from the under side of the pressure tank directly over the carbide feed opening in the hopper bottom. Gas from the pressure tank reaches the control diaphragm through the pipe nipple connection 6R. The control diaphragm and diaphragm spring, the lower section of the diaphragm housing, the valve stem and feed valve are the same as that in Fig. 1 and operate in the same manner.

Besides having the feed control and pressure tank protected by the wall of the carbide hopper and near the point of carbide feed, eliminating troublesome outside piping and tubular connections usually associated with pressure tanks mounted on the outside of the generator, there is an advantage in having carbide about the feed control housing and pressure tank to help brace and dampen vibration in the latter, particularly in a portable generator for welding purposes mounted or fixed on a motor vehicle for cross country work.

While I have shown and described in two instances devices constructed, located and mounted in accordance with my invention, it will be manifest to persons skilled in the art that many changes may be made in minor details of structure in adapting the device to various carbide hoppers, and slight changes in the mode of operation of same within the scope of the appended claims, without departing from the spirit of the invention; it is, therefore, to be understood that this invention is not to be limited to the details described and shown.

What I claim is:—

1. In an automatic carbide feed for an acetylene generator, a carbide hopper, a stationary gas pressure tank, said tank disposed substantially within the walls of said carbide hopper, a passageway adapted to admit gas

into said pressure tank, a hand operated valve associated with said passageway, said valve adapted to close said passageway whereby gas may be confined in said pressure tank, a hand hold for operating said valve, said hand hold being on the outside of the wall of the carbide hopper, a depressible resilient carbide feed control diaphragm, the upper side of said diaphragm being exposed to gas pressure from said pressure tank, and a housing for said diaphragm within the walls of said hopper.

2. In an automatic carbide feed for an acetylene generator, a carbide hopper, a stationary gas pressure tank disposed substantially within the walls of the carbide hopper, a passageway associated with said pressure tank, said passageway adapted to admit gas into said pressure tank, a hand operated valve associated with said passageway, said valve adapted to close said passageway whereby gas may be confined in said pressure tank, a hand hold for operating said valve, said hand hold being on the outside of the wall of the carbide hopper.

3. In an automatic carbide feed for an acetylene generator, a carbide hopper, a conical bottom for said hopper, a carbide outlet in the small end of said hopper bottom, a stationary pressure tank mounted substantially within the carbide hopper, a housing supported directly over said carbide outlet and within the walls of said carbide hopper, a control diaphragm disposed within said housing, means for conveying gas from the pressure tank into the housing above said diaphragm, a feed valve for regulating carbide through said carbide outlet, a stem connecting said feed valve with said diaphragm, a shield underneath said housing and above said feed valve adapted to prevent excess carbide upon the feed valve.

HERBERT G. IRWIN.
